UNITED STATES PATENT OFFICE

137,628

DESIGN FOR AN AIRPLANE

Cheston L. Eshelman, Baltimore, Md.

Application January 7, 1943, Serial No. 109,216

Term of patent 14 years

(Cl. D71—1)

To all whom it may concern:

Be it known that I, Cheston L. Eshelman, a citizen of the United States, residing at Baltimore, in the State of Maryland, have invented a new, original, and ornamental Design for an Airplane, of which the following is a specification, reference being had to the accompanying drawings, forming part thereof, in which:

Figure 1 is a front elevational view of an airplane, showing my new design.

Figure 2 is a rear elevational view of the same with the forward landing wheels retracted.

Figure 3 is front perspective view of the same from above.

Figure 4 is a similar rear perspective of the same.

Figure 5 is an angular perspective view of the same from above; and

Figure 6 is an inverted plan view of the same.

I claim:

The ornamental design for an airplane, as shown.

CHESTON L. ESHELMAN.
